DESIGN FOR A FILM REWIND

Arthur E. Gavin, Huntington Park, Calif.

Application March 18, 1938, Serial No. 75,935

Term of patent 7 years

To all whom it may concern:

Be it known that I, Arthur E. Gavin, a citizen of the United States, residing in Huntington Park, in the county of Los Angeles and State of California, have invented a new, original, and ornamental Design for a Film Rewind, of which the following is a specificataion, reference being had to the accompanying drawing, forming part thereof:

Figure 1 is a front elevation of a film rewind showing my new design.

Figure 2 is an edge elevation, looking in the direction of the arrows 2—2 of Figure 1.

Figure 3 is a rear elevation of my said film rewind, looking in the direction of the arrows 3—3 of Figure 2.

Figure 4 is a sectional view taken on the line 4—4 of Figure 1.

I claim:

The ornamental design for a film rewind substantially as shown.

ARTHUR E. GAVIN.
